Des. 240,262
Patented June 8, 1976

240,262

COMBINED LAMP AND PLANT STAND OR SIMILAR ARTICLE

Benny-Loy Dalgaard-Hansen, Tilburg Alle 20,
DK-2792 Store Magleby, Denmark

Filed Jan. 6, 1975, Ser. No. 538,582

Term of patent 14 years

Int. Cl. D11—02; D26—03
U.S. Cl. D48—31

FIG. 1 is a perspective view of a combined lamp and plant stand or similar article, showing my new design;

FIG. 2 is a top view thereof; and

FIG. 3 is a side view thereof.

The lower end of the central pole is shown as being broken off to indicate indeterminate length.

I claim:

The ornamental design for a combined lamp and plant stand or similar article, as shown and described.
